DOW B. HUGHES, OF CLEVELAND, OHIO, ASSIGNOR, BY MESNE ASSIGNMENTS, TO
MOTOR IGNITION & DEVICES COMPANY, A CORPORATION OF WEST VIRGINIA.

IGNITION SYSTEM.

1,389,647.

Specification of Letters Patent.

Patented Sept. 6, 1921.

Application filed October 22, 1910, Serial No. 588,426. Renewed September 1, 1920. Serial No. 407,505.

To all whom it may concern:

Be it known that I, Dow B. HUGHES, a citizen of the United States, residing at Cleveland, in the county of Cuyahoga and

5 State of Ohio, have invented a certain new and useful Improvement in Ignition Systems, of which the following is a full, clear, and exact description.

This invention relates to ignition systems 10 and is designed as an improvement over the systems disclosed in my pending applications for ignition systems, Serial No. 553,111, filed April 2nd, 1910, and Serial No. 557,889, filed April 27th, 1910. The object of the 15 present invention is to provide an ignition system which possesses all the advantages of my prior systems but which is simpler, consists of fewer parts and is less expensive to install than the latter.

20 The system arranged and operated in accordance with the present invention is, generically considered, similar to the systems of my prior applications in the respect that the igniting spark is produced by first discharging across the spark electrodes a high frequency current which produces an arc of low heat value and materially reduces the resistance of the air gap, and by then following up this arc with an arc of high heat 25 value and long duration produced by current passing across the electrodes directly from the main source of current, the high frequency current being preferably created by the rapid charging and disruptive discharge 30 of a condenser produced by the operation of a suitably arranged make and break device and being transmitted to the spark plug by a disruptive discharge coil.

In the present case I employ for a multi- 40 spark plug ignition system a single condenser, preferably of small capacity and a single disruptive discharge coil and distribute the high frequency current through a distributer to the different spark plug con- 45 nections which are also directly connected to the source of current so that as the high frequency current is discharged across the terminals of each spark plug, it will be im- 50 mediately followed up by current from the source of current, producing successively at the different spark plugs, arcs of low heat value and arcs of high heat value which insure total ignition of the mixtures in the cylinders.

55 My invention may be further briefly sum-

marized as consisting in certain novel combinations and arrangements of parts which will be described in the specification and set forth in the appended claims.

In the single figure of the drawings, I 60 have shown diagrammatically a system embodying my invention.

Referring now to the drawing, 10 represents a source of current which as here shown is a magneto having an armature provided 65 with a coil 11 which need be wound for very low voltages only, inasmuch as the voltage required to create an arc of high heat value after the arc of low heat value is formed by the high frequency current is very small as 70 compared with the voltages required with ignition systems commonly employed, even the systems known as low voltage systems. One terminal of the winding 11 is grounded 75 as shown, and the other terminal is connect- ed by conductor 12 to both the primary 13 and the secondary 14 of a disruptive dis- charge or high frequency coil, the primary being connected to a condenser 15 in series relation and then to ground. The coil is 80 preferably of low reactance or inductance in order that it will have little impedance or choking effect on the high frequency cur- rents. The condenser will be of small ca- 85 pacity in order that it will be fully charged by the magneto at the opening of the make and break device, as will be explained. The secondary 14 is connected by a conductor 16 to the movable member 17 of a distributer, the stationary contacts or segments 18 of 90 which are connected to the different spark plugs 19. In this particular instance, the system is arranged for four cylinders or spark plugs. Consequently, this distributer

has four segments 18, but the number of 95 spark plugs may be other than that here shown as the system will operate as effec- tively with any number of spark plugs as with four, without necessitating the use of more than one coil and one condenser. I 100 also employ for the purpose of creating the high frequency currents a make and break device including, as here shown, a lever 20 having at its end a contact which coöperates with a contact of an adjustable member 21, 105 the lever being connected by a conductor 22 to the source of current between the latter and the coil, and the member 21 of the make and break device being grounded, as shown. The make and break device is operated peri- 110

odically by a cam 23, which together with the distributor will be driven from the magneto shaft or by other means at the usual rates of speed. It will be noted that the 5 make and break device is in parallel with the armature winding and short circuits the same each time it is closed.

The operation of the system is substantially as follows: When the make and break 10 device is closed, the armature winding is short circuited, and energy is stored in the winding during the interval that it is short-circuited. At the opening of the short circuiting device, the condenser is charged by 15 absorbing the energy previously stored in the source and is thence rapidly disruptively discharged, causing the high frequency current to be set up in the primary 13 which as before stated is in series with the condenser. 20 A high frequency current is thus induced in the secondary 14 and as it is of high voltage and low amperage, it will cause an arc of low heat value to be established at that spark plug which is connected to the segment 25 engaged by the movable member of the distributor at the instant that the make and break device is opened. As soon as the arc of low heat value is established, it reduces the resistance of the gap of that particular 30 plug, and as the plug is connected through the secondary 14 directly to the source of current, an arc of high heat value will be immediately established by current passing from the source of current, the resistance of 35 the air gap being reduced to an extent such that the arc of high heat value can be established by current from the source of current at a very low voltage. The first arc, namely that produced by the high frequency current 40 is, as before stated, of low heat value and is in fact of insufficient heat value to ignite the mixture, but the arc which follows the arc of low heat value is of such high heat value and of such duration that total ignition is 45 assured and further there is no danger of the cylinder missing fire.

As the distributor arm rotates from one segment to another, the make and break device is closed and then opened so that the 50 high frequency currents are distributed or set up successively at the spark plugs connected to the successive segments engaged by the movable member of the distributor. Consequently, arcs of high heat value will 55 be established successively at the different plugs in the manner above stated.

As before stated, the rapid charging and discharging of the condenser is set up by the opening of the make and break device. To 60 make clear the action of the condenser, it may be said that on the opening of the make and break device which had previously short circuited the armature winding, the condenser is charged by the source of current to its full 65 capacity, this being assured by providing a

condenser of small capacity as compared with those which are ordinarily employed in ignition systems. As soon as the condenser is charged, and while the contacts of the make and break device are slightly separated, the condenser is then rapidly disruptively discharged, the high frequency current produced thereby continuing until or substantially until the make and break device is again closed. The condenser circuit 70 or high frequency circuit may be traced as follows:—primary 13, condenser 15, ground, make and break device, and conductor 22, back to primary 13. The make and break device which periodically short circuits the 80 armature therefore plays an important part in the establishing of the high frequency current, inasmuch as it serves as a spark gap device across which the condenser discharges take place. The width of the air gap at the 85 make and break device need not be very large and can be adjusted as circumstances require, and the arcing which occurs between the contacts of the make and break device by the discharging of the condenser 90 is of such low heat value that no material damage or injury is done to the contacts.

Having thus described my invention, what I claim is:

1. In an ignition system for a plurality 95 of spark plugs, a source of current, a distributor having stationary contacts connected to the spark plugs, and its movable member connected to the source of current so that current from said source may be distributed to the several plugs, a condenser, and a disruptive discharge coil, the condenser being connected to the source so that it may be charged thereby and having in its discharge circuit, the primary of the coil, 100 and the secondary of the coil being connected to the movable member of the distributor, and means for periodically causing the charging and disruptive discharging of the condenser.

2. In an ignition system for a plurality of spark plugs, a distributor having its stationary members connected to the several plugs and its movable member connected to the source of current, a condenser and a disruptive discharge coil, the condenser having a series connection with the primary of the coil and the secondary of the coil being connected to the movable member of the distributor, and a circuit breaker adapted to 115 periodically short-circuit the source of current.

3. In an ignition system for a plurality of spark plugs, a source of current, a disruptive discharge coil, a condenser, a distributor 120 having a rotary arm and stationary members connected to the different spark plugs, the condenser and primary of the coil being in series and being connected to the source of current, and the secondary of the coil 130

being connected in circuit with said source of current and being connected to the movable member of the distributor, and hence to the different spark plugs as the distributor arm is rotated, and means coöperating with the condenser and connected therewith to cause the same to be periodically charged and discharged.

4. In an ignition system for a plurality of spark plugs, a source of current, a disruptive discharge coil, a distributor having a rotary arm and stationary members connected to the different spark plugs, the secondary of the coil having one terminal connected to the source of current and the other terminal connected to the distributor arm, the secondary and each of the different spark plugs being in the main circuit of said source of current as the distributor arm is rotated, 15 the condenser and primary of the coil being in series and being connected also to the source of current, and a periodically operated make and break device connected to the source of current.
- 20 5. In an ignition system for a plurality of spark plugs, a source of current, a disruptive discharge coil, a distributor having a rotary arm and stationary members connected to the different spark plugs, the secondary of the coil having one terminal connected to the source of current and the other terminal connected to the distributor arm,

the secondary and each of the different spark plugs being in the main circuit of said source of current as the distributor arm is rotated, 35 and condenser and primary of the coil being in series and being connected also to the source of current, and a make and break device for periodically short circuiting the source of current.

40 6. In an ignition system for an internal combustion engine, means for producing a periodically fluctuating current, including an element operated in synchronism with the cyclic period of the engine, a disruptive discharge coil, a condenser, a distributor having relatively moving members for selectively distributing ignition current to a plurality of spark plugs, the condenser and primary of said coil being in series and being 45 connected to the source of current, and the secondary of the coil being connected in circuit with said source of current and being connected to the distributor, whereby said secondary is selectively placed in circuit 50 with said spark plugs as the distributor functions.

55 In testimony whereof, I hereunto affix my signature in the presence of two witnesses.
